No Model.)

A. L. BOLLES.
REVOLVING WINDOW SASH.

No. 554,231.

Patented Feb. 11, 1896.

UNITED STATES PATENT OFFICE.

ARCHIBALD L. BOLLES, OF BROOKLYN, NEW YORK, ASSIGNOR OF ONE-HALF
TO FRANK C. KOHART, OF SAME PLACE.

REVOLVING WINDOW-SASH.

SPECIFICATION forming part of Letters Patent No. 554,231, dated February 11, 1896.

Application filed July 5, 1895. Serial No. 554,995. (No model.)

To all whom it may concern:

Be it known that I, ARCHIBALD L. BOLLES, a citizen of the United States, residing at the city of Brooklyn, in the county of Kings and State of New York, have invented a new and useful Improvement in Window-Sashes, of which the following is a specification, reference being had to the accompanying drawings, forming a part thereof, in which similar letters of reference designate like or equivalent parts wherever found throughout the several views.

My invention relates particularly to improvements in the supports for window-sashes, and the object thereof is to provide means whereby the sashes may be revolved so as to provide means for the proper ventilation of apartments, and also to provide supports for window-sashes which are provided with counterbalance-weights and which may be raised or lowered and which may also be revolved at any point at which they may be supported; and with these and other objects in view the invention consists in the construction, combination, and arrangement of parts hereinafter described and claimed.

The invention is fully disclosed in the following specification, of which the accompanying drawings form a part, in which—

Figure 1 is a side elevation of a window-frame, together with the window-sashes mounted therein, said window-sashes being supported according to my invention and the upper sash being slightly tilted on its pivotal supports; Fig. 2, a section on the line 2 2 of Fig. 1; Fig. 3, a section on the line 3 3, and Fig. 4 a section on the line 4 4.

In the drawings forming part of this specification, A represents the vertical bars of the usual window-frames, B the top thereof, and C the bottom, and the side bars A are provided with the usual beads or strips D, E, and F, between which the separate sashes are mounted, and in the practice of my invention I support the separate sashes of the windows, which are shown at G and H, in the following manner:

The separate vertical beads or strips D and F form two vertical spaces, in which the sashes are mounted in the usual manner, and in each of these vertical spaces I place ver-

tically-movable stiles or bars K. The stiles or bars K are preferably of the same length as a window-sash with which they are connected, and secured to these stiles or bars in any preferred manner are the cords M, by which the windows are supported, said cords being connected with weights N, arranged in housings at the sides of the frame in the usual manner.

Each of the stiles or bars K is provided on its outer side with a plurality of springs O, which are preferably three in number, one at each end and one in the middle, and these springs, or the upper and lower ones, are adapted to bear upon the inner surface of the sides of the frame.

The springs O are plate-springs, and the ends of the upper and the lower springs are preferably directed outwardly and the convex surface thereof inwardly, and the ends of the middle springs are preferably directed inwardly and the convex surface thereof outwardly, and passing through to the middle springs are the pivot-pins P, by which the window-sashes are supported, said pins being secured in the sash-frames and revoluble in the said stiles or bars and in the springs through which they pass and being provided with heads on their outer ends which hold the springs in place.

The central portions of the inner vertical sides of the stiles or bars K are convex in cross-section, as clearly shown at R in Figs. 2, 3, and 4, and the corresponding parts of the sides of the frames of the window-sashes are concave in cross-section, as shown at S in Figs. 1, 3 and 4, and when the window-sashes are closed, as shown at the lower part of Fig. 1 and in cross-section in Fig. 3, the vertical convex portions of the stiles or bars fit within the vertical concave portions of the sides of the window-sashes, and there is a narrow space between the stiles or bars and the sides of the frames, as shown at T in Figs. 1 and 3.

The stiles or bars K are of such depth as to project beyond the beads or strips D, E and F, and whenever it is desired to open or revolve one of the sashes on its supports it is only necessary to catch hold of either the lower or upper end thereof and to pull inwardly or shove outwardly thereon, as will

be readily understood, and this operation will result in turning the sash on its pivotal supports, as shown in Figs. 1, 2 and 4, and in this operation the stiles or bars K are forced 5 outwardly, so as to fill, or nearly fill, the space T between the same and the sides of the window-frame, and by reversing this operation the sash may be returned to the closed position, in which position the stiles or bars K 10 will be forced inwardly by the springs O, as shown in Figs. 1 and 3.

It will be understood, of course, that either 15 of the sashes, the upper or the lower one, may be turned or revolved independently of the other, or that both of said sashes may be turned or revolved together, and it will also be understood that when it is desired to revolve the lower sash it must be raised, so that the lower side thereof will be freed from the 20 strips or beads of the bottom of the frame, and when it is desired to revolve the upper sash the same must be lowered, so that it will be removed from the strips or beads at the top of the frame, which are not shown.

25 In the construction herein described, the pivot-pins P, or the outer ends thereof, are secured to the central springs O, and said pivot-pins are free to slide in both the stiles or bars K and the sides of the frames of the 30 window-sashes, as will be readily understood, and by reason of the vertical convex central portion of the outer side stiles or bars K, and the corresponding vertical concave central portion of the outer sides of the frames of the 35 sashes, the operation of revolving the said sashes is rendered simple and effective, and the sashes are held stationary and securely at any desired point by means of pressure exerted by the springs O, and in these features 40 of construction my improvement differs from all devices of this kind heretofore employed.

Having fully described my invention, I claim and desire to secure by Letters Patent—

1. In combination with a window-frame, of the usual form, of the vertically-movable stiles or bars having a convex outer surface, cords attached to weights passing over rollers or pulleys in the frame of the window, the opposite end of said cord being attached to said 50 stiles, window-sashes having a concave longitudinal groove in the edges thereof adapted to receive the convex portion of said stiles, flat springs secured at each end and the middle of said stiles, pivot-pins passing through 55 said stiles and said middle springs and connecting the vertically-movable stiles and the frame of the sash, whereby said sash may be tilted in any position, substantially as described.

2. In combination with a window-frame, of the usual form, of the vertically-movable stiles or bars having a convex outer surface, cords attached to weights passing over rollers or pulleys in the frame of the window, the opposite end of said cord being attached to said 60 stiles, window-sashes having a concave longitudinal groove in the edges thereof adapted to receive the convex portion of said stiles, flat springs secured upon the ends of said 70 stiles, having a concave portion thereof toward the frame of the window and a middle spring having a concave portion thereof extending toward the frame of the sash in opposite direction to the end springs, pivot-pins passing 75 through said stiles and said middle spring and connecting the vertically-movable stile and the frame of the sash, whereby said sash may be tilted in any position, substantially as described.

In testimony that I claim the foregoing as my invention I have signed my name in presence of the subscribing witnesses.

ARCHIBALD L. BOLLES.
